UNITED STATES PATENT OFFICE.

ERWIN A. GEIGER, OF WESTFIELD, AND ADOLPH GEIGER, OF ELIZABETH, NEW JERSEY, ASSIGNEES, BY MESNE ASSIGNMENTS, TO ELLIOTT ADDRESSING MACHINE COMPANY, A CORPORATION OF MASSACHUSETTS.

HAND-OPERATED ADDRESSING MACHINE.

Application filed November 16, 1927. Serial No. 233,539.

This invention relates to addressing machines generally, but is more specifically designed to produce a small, hand-operated mechanism employing stencils as the principal form of the address bearing strip, such small mechanism, however, being capable of printing, skipping or repeating with each one of the series of addressing bearing strips and with the same facility as characterizes much 10 larger power-driven mechanisms now on the market. An important advantage of the present invention also is that with the exertion of a reasonable amount of pressure by the hand of the operator, a very great pressure 15 is produced on the inking pad when pressed against the stencil, so as to ensure forcing an adequate amount of ink through every opening in the stencil. This pressure is uniform for any one adjustment of the 20 apparatus.

The best form of apparatus at present known to us embodying the invention is illustrated in the accompanying 7 sheets of drawings in which:

25 Fig. 1 is a front view of the machine with the handle and ink bearing platen raised.

Fig. 2 is a similar rear view.

Fig. 3 is a plan view showing the handle and inking platen down in printing position.

30 Fig. 4 is a section on a vertical plane taken on line 4—4 of Fig. 3, parts being broken away.

Fig. 5 is a similar view with the parts shown in the position assumed when the handle and inking mechanism are raised.

Fig. 6 is an enlarged detail side elevation of the handle and a portion of the card feed apparatus, the portions in dot and dash lines indicating disengagement of the card feeding

40 apparatus, so that repeated printings can be made from the stencil then in printing position.

Fig. 7 is a detail section taken on line 7—7 of Fig. 3, illustrating the operative position 45 of the stencil skipping attachment.

Fig. 8 is a diagrammatic detail illustrating coaction between the inking pad or platen, and the ink reservoir, by which latter the ink supplied to the platen is renewed during each 50 cycle of operations of the machine, and

Fig. 9 is a detail side view of the inking platen and its supporting device on an enlarged scale.

Throughout the drawings like reference characters indicate like parts.

1 is the base of the machine, usually made, as shown in the form of a small table 1, with rubber pads 1^a on the feet of the table so that the whole machine may be placed upon the surface of a desk or of another table without marring the same. 2 is the card magazine which is located at one end of the base 1 to hold a stack of the cards 3, as shown in Figs. 4 and 5. A flexible set of card guides 4 extend from the base of the card magazine 2 under the inking mechanism, and have their free ends 5 in position to discharge the used cards into the card receptacle 2^a (see Figs. 1, 2, 3, and 5). This card receptacle 2^a is supported on the arm 74 which swings on a vertical pivot bearing, as shown at 75, which latter is separable so that the card receptacle may be removed if desired. This flexible set of card guides consists of two parallel strips of steel, longitudinally grooved on their inner edges, and having their rear ends supported on upwardly inclined bases 7 so that normally the free ends 5 of these card guides are raised above the surface of the table 1, as shown in Fig. 5. When the inking mechanism is forced down upon these flexible card guides they are bent down upon the table as shown in Fig. 4. Guide pins 56 are carried by the clip 55 (Fig. 5) on these card guides to co-operate with slots in the table surface (not shown) and thereby confine the motion of the card guides to vertical planes. The guide pins 56 may be removed when long sheets of paper are to be printed, as will be hereinafter described.

The cards 3 are fed from magazine 2 to the inking mechanism by means of a reciprocating plate 6 (Figs. 3, 4 and 5) which slides back and forth in the rear ends of the card guides and has projecting portions 60, 60 at each forward corner adapted to abut against the rear edge of the bottom card in the magazine 2 and force it out along the guides toward the inking mechanism.

The mechanism for reciprocating the card feed plate 6 here shown is the following: 61 is a lug stamped upon the rear of plate 6 which is engaged by the adjustable screw 8 and nut 58, the former being set in the cross arm 7 (Figs. 2, 3 and 4) which is carried by the slide 9 moving in guide 59 and having rack teeth

10 cut on its under edge. 62 is a stop against which the forward end of slide 9 may abut. This stop is adjustable, being threaded into the frame 1, and 63 is a jam nut for holding it in any position of adjustment. 11 is a gear wheel meshing with rack 10 and carried by short shaft 14 which passes through one end of link 15 and, on its outer end, carries the smaller gear wheel or pinion 12 which rests on, and cooperates with, the fixed rack 13, supported from the main frame of the apparatus. Accordingly, when link 15 is pulled to the left, looking at Fig. 4, the shaft 14 will be pulled in that direction and also rotated 15 in a counter-clockwise direction and this motion will be transmitted by gear 11 to the slide 9 and plate 6 for a card feeding operation. Evidently, also, any motion of link 15 will be multiplied several times by the time it is thus transmitted to slide 9 and plate 6.

The means shown for actuating link 15 comprise the feed lever 17, the lower end of which is pivoted to link 15 at 16, while its upper end 19 is notched to engage the dog 20 pivoted at 21 to a swinging member 22, which, like lever 17, is pivoted to the main frame by shaft 18. This lever 22 is one of two swinging members so marked and shown in Fig. 3, each of which has an upwardly curved extension 22^a at its free end (see Fig. 5). These curved ends together carry the inking mechanism. When the pawl 20 is in the position shown in Fig. 5, it fits closely into the notch in the end 19 of the card feeding lever so that the latter is positively reciprocated up and down by the corresponding movements of the swinging members 22, 22. If, however, the dog 20 is tilted up into the dot and dash line position shown in Fig. 6, then the card feed lever 17 will not be effected by any downward movement of swinging member 22 and the card feed mechanism will be thereby disabled. This tipping of dog 20 is accomplished through the engagement of its projection 20^a by the repeat lever 23 which will be hereafter described. 27 is a finger projecting downwardly from the pivoted end of one of the members 22 and connected to tension spring 28, anchored to the main frame at 29. This spring normally holds the parts in the position shown in Fig. 5.

The means for oscillating swinging members 22 and thereby operating the entire machine comprise the yoke 73, pivoted to members 22 at 22^b (Figs. 4 and 5), and carrying the handle 25 at its free end. The pivoted ends of yoke 73 have crank-like extensions 72, one of which carries friction roller 71, and the other a similar friction roller 71^b, which cooperate respectively with stationary friction rollers 70, 70^b mounted on the pivoted pressure housings 68, 68^b. These pressure housings are pivoted on the common pivot shaft 18 and are adjustable by means of screws

68^a passing through the rear ends of the housings and engaging the table base 1. Each longer screw 68^a is a tension screw, and each shorter one a pressure screw, and by these the housings 68, 68^b may be accurately adjusted, and positively held, in position.

The housing 68^b also has, in its inner face the camway 69 shown in detail in Fig. 7, in which camway the roller 71^b, carried by one of the short arms 72 of the handle yoke, runs back and forth as the swinging members 22 rise and fall. The parts are so proportioned that when the swinging members 22 and the handle 25 carried thereby rise under the action of spring 28 into the position shown in Figs. 1, 2 and 5, the handle yoke 73 is thrown up into the vertical position there shown.

The handle 25 is made hollow, as shown, and in it is placed the spindle 26 carried by the repeat lever 23 which is pivoted to the yoke 73 at 24 and at its other end, engages the extension 20^a of dog 20. Normally, spindle 26 is maintained in the position shown in Fig. 5 by the spring 25^a shown in Figs. 1 and 3, so that pawl 20 is left in engagement with the forked end 19 of the card feed lever 17, but if the operator moves spindle 26 by his thumb or finger against the resistance of spring 25^a, he will thereby trip pawl 20 and disable the card feed mechanism.

The preferred form of inking mechanism shown comprises the following elements: 30 is an inking pad having a slightly curved face and is carried by the block 30^a, supported by pivot shaft 31 mounted in the curved ends 22^a of the swinging members 22. A small gear wheel 32 is mounted on shaft 31 and is locked to hub 31^b on block 30^a by clutch joint 32^a, as shown in Fig. 1, so that rotation of gear 32 will also rotate the inking pad 30. Idler gears 33 and 33^a are also mounted on curved extensions 22^a, the former by a short stud shaft, and the latter by a long shaft 33^b, which extends across from one member 22^a to the other. 34 is another gear meshing with gear 33^a and mounted on stud shaft 36 carried by 22^a (see Fig. 3) which stud shaft supports one end of the cylindrical ink fountain 35, the other end of which is journalled on the removable screw bearing 76. The gear 34 also meshes with the sector rack 37, carried by the frame 38, the lower end of which frame is supported on pivot shaft 18, while its angular position is fixed by pin 38^a passing through a hole in an upwardly projecting lug from frame 38, as shown in Figs. 2 and 5.

This gearing is so apportioned and adjusted that when the swinging members 22, and parts carried thereby, are raised into the position shown in Fig. 5, the ink pad 30 will be in the position there shown, and, as the swinging inking mechanism is forced downward by means of the handle 25 into the position shown in Fig. 4, the gear 34, rolling over

sector rack 37 will rotate the ink fountain 35 in a counter-clockwise direction (looking at Figs. 4 and 5) and rotate inking pad 30 in a clockwise direction through three-fourths of 5 a revolution, with the result that it will roll over the face of the ink fountain, acquire a fresh coating of ink, and then come down on the stencil beneath it with its final downward motion. On the under sides of the outer ends 10 of swinging members 22 are rubber pads, one of which is shown at 77 in Fig. 7. These rest on card guide strips 4, 4, when the swinging mechanism comes down, and force them down upon table 1, just before the inking pad 15 touches the stencil.

The ink fountain, as shown, consists of a semi-cylindrical shell 46, of perforated or reticulated construction (see Fig. 8) supported by the back 48 and covered by the blanket 47 20 of absorbent material. Back 48 has a filling duct 49, closed by screw plug 49^a and an air vent 50 which is left open during the filling operation. The ink fountain is journaled in the swinging frame 44, pivoted on the shaft 25 33^b (see Fig. 7), and said frame or housing is made adjustable toward and from the ink pad 30 by means of the adjusting screw 45 which threads through a transverse hole in the cross bar 64, which cross bar engages the 30 forked free end of the housing 44, the lower end of said screw 45 being swivelled in the cross bar 65 which is journaled in the lugs 66 projecting from the pivot shaft 22^b of the handle yoke 73. A spiral spring 67 surrounds 35 shaft 65 and is anchored at one end to the pin 66^a projecting from the housing 44, and at the other end is fastened to said shaft 65 so as to normally hold the parts in the position shown in Fig. 7. When screw 45 is backed 40 off so that cross bar 64 is loosened, it may be swung down so that cross bar 64 will no longer engage the forked end of housing 44. The plate 44^a normally serves to maintain 45 these parts in the operative position shown in Fig. 7.

To enable the operator to skip one or more cards the following skip mechanism is provided. 39 is a lever pivoted to yoke 73 at 40. It has an upwardly projecting thumb piece 50 39^a by which it may be manipulated. Normally it is held in the position shown in Fig. 4 by means of the curved spring 42 fast on housing 73, and with its curved portion, engaging pin 43, projecting from one side of 55 lever 39. While in this position, lever 39 has no function whatever, but if thumb piece 39^a is pressed down, as indicated in Fig. 7, so as to swing the lower end of lever 39 in line with the hub 31^b of the ink pad block 30^a, the concave end 41 of lever 39 will engage said hub as the handle yoke 73 swings down before the swinging members 22 and the inking mechanism carried thereby have come down far enough to cause ink pad 30 to press upon 60 the stencil card or pads 77 to press card 65

guides 4, against table, the parts being then locked in the position shown in Fig. 7. As a result no printing is affected, and when the handle 25 is swung up again into the position shown in Fig. 5, the stencil card at the end of 70 the guides 4 is forced out into the card receptacle 2^a and another card advanced to printing position. As many cards can be skipped as is desired by repeating this operation. 75

The mechanism so far described suffices for printing envelopes and short sheets of paper. After each cycle of operations of the machine a stencil card appears at the free end of the card guides 5 exposed so that the operator 80 can read it. If he desires to print an envelope from it, he places the envelope under the free ends of the card guides and swings the handle 25 downward, with the result that the inking pad 30 is then forced down upon the card and envelope with great pressure, the friction rollers 71, 71^b passing under the pressure rollers 70 and 70^b as the handle 25 reaches its most extended position in a horizontal direction with the result that the yoke 73 and its 85 upwardly projecting lug 72, carrying said friction rollers, form a powerful cam lever, through the operation of which a slight downward pressure on handle 25 produces a very great pressure of the ink pad on the 90 stencil card. 5^a (Fig. 5) represents one of a pair of rubber pads which yield slightly to form an elastic support for the envelope and the free ends 5 of the card guides 4 during 95 the printing operation. When the handle 25 is released, the spring 28 lifts the mechanism into the position shown in Figs. 1, 3 and 5, the feed plate 6 is pulled forward to shove out another card from the magazine 2, which card pushes the one in front of it into printing 100 position, the used card having been discharged into the receptacle 2^a, and the parts are ready for another operation. During downward motion the part, plate 6 is drawn back to engage another card at the bottom of the stack 105 in magazine 2. 110

If it is desired to print upon long sheets of paper, the guide pins 56 and supporting clip 55 are removed, and sliding plates 52 are pulled out laterally from table 1, leaving an 115 opening 51, in the surface of the table, beneath which extends the chute member 53. Long sheets of paper can then be slipped in and slid down through this slot over said chute member, leaving their rear ends in 120 printing position. 125

If it is desired to print from a roll of paper, such roll can be mounted upon the shaft 54 at the rear of the machine, (see Figs. 3 and 5) and the paper threaded up through space 51 and out into printing position. 125

Both magazine 2 and card receptacle 2^a can be made adjustable to accommodate cards of different sizes as to width. Such an adjustment is indicated in Fig. 3 where an extra set 130

of holes 78 are shown which may be used for fastening one side of the magazine 2 when it is moved in to accommodate narrower cards. Receptacle 2^a is also made in two parts, 5 screwed together at 79, 79, and a similar extra pair of holes are shown at 80, 80.

30^b (see Fig. 9) is a large headed screw mounted in the side of the block 30^a which supports the inking pad 30 as before described. 10 One side of the head of this screw is cut away at 30° sufficiently so that, if the screw is turned 180 degrees from the position shown in Fig. 9, this cut away portion will enable it to clear the edge of pad 30, which 15 may then be slid out laterally from its seat in the block 30^a, to which block it is normally held by being seated in the grooves 30^a.

81 is a laterally adjustable stop guide for the envelope or sheet being printed, it being 20 laterally adjustable by means of the slot and thumb screw shown in dotted lines in Fig. 3. The guide pins 56, being adjustable longitudinally of the flexible card guides 4 by means of the sliding clip 55 on which they 25 are carried, serve as longitudinally adjustable guide stops for the envelope or other small article being printed. When the guide pins 56 are removed to permit the long sheets or roll of paper to be printed, the laterally 30 adjustable guide 81 still functions.

Various changes could be made in the details of construction here illustrated without departing from the underlying principles of the invention. Thus, while stencil cards are 35 shown as an element of the printing mechanism, cooperating with the inking device to print the envelopes or paper sheets on which the machine operates, other forms of address bearing strips could obviously be substituted 40 for such stencil cards. Also some of the sub-combinations of mechanism shown could be omitted without interfering with the operativeness and usefulness of the remaining mechanism.

45 Evidently the pressure which the lever cam system, operated by the handle, exerts upon the inking pad when it rests upon the stencil may be varied somewhat according to the extent to which the friction rollers 71 and 71^b 50 roll under the stationary friction rollers 70, 70^b, mounted on the pivoted pressure housings 68, 68^b, and also upon the vertical adjustment of these stationary rollers 70, 70^b, and that consequently this pressure function may 55 be modified by adjusting the position of the pressure housings through manipulation of the screws 68^a, as previously explained. When the housing has been given any one adjustment, the pressure of the inking pad 60 upon the stencil will then be constant for that adjustment for every operation in which the handle is forced as far down as is possible with that particular adjustment.

Having described our invention, we claim:

65 1. In a hand operated printing apparatus em-

ploying stencils, the combination, with a main frame, a series of said stencils and means for feeding them consecutively into printing position on said main frame, of an ink bearing pad, a lever system for pressing said pad 70 down upon any stencil in printing position on said main frame, a handle for operating said lever system, and means whereby a uniform pressure exerted on said handle may be progressively increased upon said pad as said 75 handle approaches its final pressure exerting position.

2. An apparatus such as defined in claim 1 in which said lever system comprises a swinging member pivoted at one end to said main frame, and extending in a generally horizontal direction, in which member said inking pad is mounted and to a free end of which said handle is pivoted and held normally in an upright position; whereby the distance of 80 said handle from the pivot of said swinging member is progressively increased as the handle is pulled downward by the operator.

3. An apparatus such as defined in claim 1 in which said lever system comprises a swinging member pivoted at one end to said main frame and in which member said inking pad is mounted, a handle pivoted to the free end of said member, a pressure member rigidly mounted on said main frame, and a cam connection between said handle and said pressure member which is adapted to be brought 90 into action as the handle approaches its lowermost position.

4. An apparatus such as defined in claim 1 in which said lever system comprises a swinging member pivoted at one end to said main frame and in which member said inking pad is mounted, a handle pivoted to the free end of said member, a pressure member 100 rigidly mounted on said main frame, and a cam connection between said handle and said pressure member which is adapted to be brought into action as the handle approaches 105 its lowermost position.

5. An apparatus such as defined in claim 1 in which said lever system comprises a swinging member pivoted at one end to said main frame and in which member said inking pad is mounted, a handle pivoted to the free end of said member, a pressure member rigidly mounted on said main frame, and a cam connection between said handle and said pressure member which is adapted to be brought into action as the handle approaches 115 its lowermost position, said cam connection comprising an anti-friction roller mounted on said pressure member and a co-operating anti-friction roller carried by a lug projecting from said handle at its pivotal point.

6. In a hand operated printing apparatus, the combination, with a main frame adapted to serve as a pressure platen, of a swinging member pivoted to said main frame and ex-

- tending in a generally horizontal direction from its pivot, an ink bearing pad mounted on said swinging member, a handle pivoted to a free end of said swinging member, and 5 means for automatically raising said handle to an approximately vertical position when said pad is lifted from said main frame and for shifting it to an approximately horizontal position at or about the time said pad is lowered into printing position. 10
7. A combination such as defined in claim 6 in which said handle shifting means comprises a member rigidly mounted on said main frame provided with a cam groove, and 15 a projection from said handle engaging said cam groove.
8. An apparatus such as defined in claim 6 combined with spring mechanism normally tending to raise said pad. 20
9. In a hand operated printing apparatus comprising a main frame adapted to serve as a pressure platen, a swinging member pivoted to said main frame, an ink bearing device carried by said swinging member, 25 a handle by which said member and ink bearing device carried thereby may be vibrated toward and from the platen portion of said main frame, the combination, with said above recited apparatus, of means associated with 30 said handle, and under control of the hand grasping it, for checking any downward movement of said ink bearing device just before it comes into printing relation with the platen portion of said main frame. 35
10. A combination such as defined in claim 9 in which said checking means comprises a mechanism by which the position of said handle relative to said swinging member is positively varied as said inking device approaches said platen, and an adjustable locking element mounted on said handle and adapted, when in locking position, to engage said swing member and prevent further movement of said handle relatively to 45 said member.
11. In a hand operated addressing machine the combination of a main frame adapted to serve as a stationary platen, a swinging member pivoted to said main frame, an ink carrying pad mounted on said member and means for oscillating said member toward and from said frame, a series of address bearing strips, and guides therefor extending under said pad, a reciprocating member adapted to feed said strips along 50 said guides, an oscillating member pivoted intermediate of its ends to said main frame and having a connection from one of its ends to said reciprocating member and provided at its other end with a detachable connection to said first mentioned swinging member; whereby said strip feeding mechanism may be disabled at will, and repeated printings made from any one address bearing strip then 55 in printing position by breaking said detachable connection. 65
12. A combination such as defined in claim 11 in which said detachable connection comprises a dog pivoted on said swinging member engaging said oscillating member and a manually operated device for holding said dog temporarily out of engagement with 70 said oscillating member.
13. In an addressing machine the combination of a platen, an ink bearing pad and means for causing one of these elements to reciprocate toward and from the other, a pair of flexible, elastic card guides each fixed at one end and having their free ends projecting between the said platen and ink bearing 75 pad at a point approximately midway between the two when they are separated to substantially the maximum extent, a series of stencil cards in said guides and means operated in synchronism with the moving apart 80 of said first mentioned elements to feed said cards along said guides toward said elements; whereby, upon inserting an article to be printed between said platen and guides and forcing said pad and platen together, the 85 free ends of said guides and the card carried thereby will be forced against said article and said platen, together with said ink bearing pad. 90
14. An apparatus such as defined in claim 13 combined with a pair of stop pins adjustable along said card guides and projecting through slots in said platen, against which pins an edge of the article to be printed may rest to ensure its proper registry with the 95 stencil card during the printing operation. 100
15. In an addressing machine the combination of a table-like base having a lateral slot therein, a pair of flexible card guides fastened to said table at one end and having their free ends extending across said slot and normally free from said table, and a vertically movable ink pad located over said free 105 card guide ends; whereby a long sheet of paper may be inserted under said guides and through said slot, a stencil card inserted in said guides and said pad and card pressed down on said paper and table by flexing said guides. 110
16. An apparatus such as defined in claim 15 combined with a support for a roll of paper which is to be threaded through said slot. 115
17. In a printing mechanism the combination, with a table-like base, of a swinging member pivoted at one end to said base, a rotatable inking pad and cylindrical ink fountain journalled in the free end of said member, gearing causing said pad and fountain to rotate in unison to produce temporary contact between their surfaces, a gear wheel fixed to one of said last mentioned elements, and a rack shaped in the arc of a circle 120 125

the center of which coincides with the axis of the pivot of said swinging member, which said rack is rigidly supported on said table-like base, together with means for oscillating said swinging member toward and from said base.

18. An apparatus such as defined in claim 17 combined with a hinged housing for said ink fountain, and means for swinging said housing toward or from the axis of said ink pad, whereby the pressure between the surfaces of said pad and fountain may be adjusted.

19. A hand operated addressing machine comprising, in combination, a base, a swinging member pivoted to said base, an inking mechanism carried on said swinging mem-

ber, means for intermittently feeding a series of stencil cards under said inking mechanism, a train of gearing for transmitting motion to said card feeding mechanism from said swinging mechanism, a hollow handle operatively connected to said swinging member, and means for temporarily disabling said train of gearing comprising a spindle loosely mounted in said hollow handle and projecting slightly therefrom; whereby the operator's hand grasping said handle may also manipulate said spindle and thereby disable or restore to action said card feeding mechanism.
